UNITED STATES PATENT OFFICE.

FREDERICK W. CARLSON, OF HELENA, MONTANA.

SANITARY WASHBASIN.

1,089,320.

Specification of Letters Patent.

Patented Mar. 3, 1914.

Application filed August 21, 1912. Serial No. 718,254.

To all whom it may concern:

Be it known that I, FREDERICK W. CARLSON, a citizen of the United States, residing at Helena, in the county of Lewis and Clark and State of Montana, have invented new and useful Improvements in Sanitary Washbasins, of which the following is a specification.

The present invention relates to improvements in wash basins or the like.

In carrying out my invention I propose to provide an ordinary wash basin or the like, with an inner lining of an antiseptic material, which, after being once used, is adapted to be removed from the basin and destroyed.

I also aim to provide a lining of this character, which shall be strong and durable, which will not be susceptible to the effect of the water received therein, and which may be easily and quickly applied to the basin.

A still further object of the invention is the provision of a lining of this character, which may be easily and quickly folded and suspended from a suitable rack arranged in close proximity to the basin, whereby one of the said linings may be brought into use when the lining used has been removed from the basin.

A still further object of the invention is the provision of a collapsible, destructible lining, which shall have its upper face or edge formed with a reinforcing bead or rim, which shall greatly add to the strength of the same as well as to form means whereby the lining may be sustained upon the upper face of the basin.

With the above recited objects in view and others, of a similar nature, the improvement resides in the novel formation of devices, hereinafter fully described and claimed.

In the drawing, Figure 1 is a sectional view through an ordinary lavatory basin illustrating my improvement arranged therein, the improvement being also shown in section, and Fig. 2 is a greatly enlarged detail sectional view through my improvement and taken in a line with the severing element.

Referring now to the drawings in detail, the numeral 1 designates an ordinary porcelain basin and 2 the removable, destructible, antiseptic, inner lining for the same. In this connection it may be well to state that while the improvement is illustrated as ap-

plied to a lavatory basin, the same may be employed with equal efficiency upon various other vessels.

The member 2 is constructed of some suitable cheap material, such as paper, or the like, the same being foldable and being sufficiently yieldable to snugly engage with the inner face of the basin when expanded by the water, which is delivered thereto. The member 2 has its upper edge formed with a reinforcing rim 3, the same being also formed of some destructible material, and the said rim is adapted to form a bearing to support the body of the member 2 when the same is arranged within the basin. The member 2, as well as its rim, is impregnated with some suitable antiseptic material, or the same may be provided with an inner facing of the said antiseptic material. The member 2 is further provided with a cutting element 4, the same being preferably in the nature of a cord. This cord is preferably arranged within the member 2 during the process of manufacture, but the said cord may be secured to the member in any desired or preferred manner. One end of the cord is extended beyond the bead or flange 3.

When the paper basin 2 is arranged within the lavatory basin 1 and water delivered to within the said paper basin, the body of water will cause the paper basin to expand or to be forced against the inner face of the lavatory basin 1 to snugly engage therewith, and also the body of water will necessarily soften the basin 2 so that the same may be easily destroyed. It will, of course, be understood that the body of water within the destructible basin 2 will provide sufficient resistance to permit of said basin being severed when a sharp pull is exerted upon the extending end of the cord 4 toward the center thereof, or in the direction of the longitudinal axis of the destructible basin member, and as this cord is arranged within the body of the paper basin, a sufficient length to have its end within the basin arranged either directly above or a slight distance beyond the outlet for the lavatory basin 1, the paper basin 2 when severed will permit of all of the water contained therein finding an outlet before the paper member is entirely withdrawn from the basin 1.

Having thus fully described the invention what is claimed as new is:

As an article of manufacture, an auxiliary

2
basin or lining for lavatory basins constructed of light destructible material, comprising a foldable bowl-shaped member which is adapted to be forced against the inner wall of the lavatory basin when water is delivered to within the said destructible basin, the said basin including a reinforced rim which is adapted to rest upon the top member of the lavatory basin, the said destructible auxiliary basin having therein a severing cord which extends from approximately the center of the basin to and

through the upper edge thereof and adapted when a pull is exerted thereon in the direction of the longitudinal axis of the said 15 destructible basin to split the basin to allow the water to flow therefrom to within the basin proper.

In testimony whereof I affix my signature in presence of two witnesses.

FREDERICK W. CARLSON.
